BEARING DEVICE

William T. Murden, Forestville, Conn., assignor,
by mesne assignments, to General Motors Corporation, Detroit, Mich., a corporation of Delaware

Application September 16, 1933, Serial No. 689,733

10 Claims. (Cl. 308—193)

My invention relates to bearing devices and the like—such, for example, as those devices in which load is sustained by contacting parts—and the invention is particularly applicable to anti-friction bearings, variable-speed power transmissions, and other things, which embody rolling-elements that are curved in the direction across their co-operating raceways, examples of such rolling-elements being spheres and barrel-shaped rollers, and the herein-illustrated embodiment of my invention being a ball bearing. One object is to increase endurance properties, as by distributing the stress substantially evenly over the area of engagement between the contacting parts, and another object is to greatly reduce shifting of the parts from desired mutual relationship, as by imparting increased rigidity, especially in the line of load. To these ends, and also to improve generally upon devices of the character indicated, my invention consists in the various matters hereinafter described and claimed.

Stated generally (but not by way of limitation), according to my invention, the opposing surfaces of the co-operating load-supporting members (as a ball and its co-operating race-member) are so shaped that when the device is free from load those members are, at all points beyond the desired length of their contact under load, spaced apart so far that the rated load will not cause them to interengage, but, when still free from load, those surfaces are, throughout that length of contact under load, as much in coincidence as it is possible to make them and yet permit the use of only a smooth line throughout such length of contact and for juncture with the above-mentioned portions that are not interengaged under load. One efficient and commercially practicable way of accomplishing this is by shaping the surface of one of the contacting parts as the curve of a circle, and shaping the co-operating surface of the other such part as an elliptical curve that is very nearly the curve of the said circle throughout substantially the ultimate arc of contact, has its central part tangential to said circular curve in the line of the load, throughout several degrees from the point of tangency progressively (but only most minutely) departs from the circular curve as that arc proceeds from the tangent point, then appreciably accelerates its rate of such departure as the extremities of such ultimate arc of contact are being reached, and then rapidly further increases such rate of departure substantially at and beyond the extremities of that arc.

As will more fully hereinafter appear, this results in substantially even distribution of stress over the whole length of contact under even the lightest loads, and deflection of material of the contacting elements is greatly reduced in the contact area, especially at its center, whereby the endurance properties of the device are greatly enhanced (as that it has longer life under a given load at a given speed) and the parts of the device do not materially shift from their initial, 10 and desired, mutual relationship.

In the accompanying drawing, Figure 1 is an elevation, partly in section, of a portion of a ball bearing exemplifying my invention, the view showing the bearing when not under load; Figure 2 is a plan view of a fragment of the outer race-ring of such bearing, the contact area between ball and raceway when under load being indicated by broken lines; Figure 3 is a fragmentary, diagrammatic view corresponding to Figure 1 but enlarged and with the curvature relationship necessarily exaggerated; and Figure 4 is a table of approximate radial distances between the ball surface and race surfaces of different illustrative kinds, such distances being 25 taken at points transverse the bearing.

In the illustrated embodiment of my invention the co-operating load-sustaining parts are shown as the inner (or "cone") race-ring 1 of a ball bearing, the outer (or "cup") race-ring 2 thereof, and the circular series or set of spherical balls 3. All of these load-sustaining parts are shown as commonly heretofore constructed except that, the rolling-elements 3 having circular curvature transverse the device when not under load, the curvature of each of the raceways, 4 and 5, tangent, as at 6, to the illustrated ball at the line of load (which is that of the diameter 7) is, when the device is free from load, that of an arc of an ellipse whose curvature at such point of tangency is practically that of the ball curvature and whose axis (the major axis in the illustration here given) is in the line of that before-mentioned diameter, 7, of the ball that includes the points of tangency between ball and raceways, the center of the aforesaid elliptical arc being at the before-mentioned point of tangency. One satisfactory such ellipse for a raceway to be used with a ball one-half inch in diameter is indicated at 8, Figure 1, and defined 50 by the equation

$$\frac{x^2}{(.34602)^2} + \frac{y^2}{(.29412)^2} = 1$$

in which x indicates the distance along that major axis from any point, a , in that axis to 55

the center, o , of the ellipse, and y indicates the distance, perpendicular to that axis, from that point a to the periphery of the ellipse. Many advantages, hereinafter appearing, are secured by relatively spacing the surface of the race-way and the co-operating surface of the rolling element as just above described.

Such spacing is so minute in devices of the present character that no accurate graphic illustration can be given within the limits of the accompanying drawing, but the clearance is indicated diagrammatically (and necessarily in an exaggerated way) in Figure 3, where the elliptical race-way is indicated by the surface 5, and the broken line 9 indicates the circular curve commonly heretofore given the raceway; and the clearance is also stated approximately in Figure 4, where distances are given in units of one one-hundred-thousandth of an inch and the figures 20 in the horizontal line 10 indicate degrees of the ball circle proceeding transversely from the aforesaid point of tangency, the figures in the horizontal line 11 show the clearances resulting when the transverse race curvature is (as has heretofore been common) that of a circle whose radius is substantially 51.6% of the diameter of the co-operating ball, and the figures in the horizontal lines 12 and 13 show the clearances resulting when using such elliptical curves as above indicated. But even the figures stated are necessarily only approximate.

In ball bearings and other devices of the present character it is, of course, advantageous that when under load the co-operating surfaces of the bearing members (as the ball 3 and its race-member 2) contact with each other over an appreciable length (as the arc extending to each side of the point of tangency 6), so that adequate mass of material is presented to sustain the load. In ball bearings such arc of eventual contact is commonly of total extent of from about 40 degrees to about 50 degrees of the ball circumference. But any circular transverse race-curve, even though it have a radius only barely greater than that of the co-operating ball, necessarily results in a relatively rapid divergence between ball-surface and race-surface from the instant that the curves proceed transversely away from the point of tangency, the rate of such divergence rapidly accelerating as such point is proceeded from. For example, as shown in Figure 4, line 11, when a ball of one-half inch diameter is used with a circular race-curve whose radius is but 51.6% of the ball diameter, at only three degrees from the tangent point the clearance between ball and race is well over 1 one-hundred-thousandth of an inch, at ten degrees it is almost 12 one-hundred-thousandths, and at twenty degrees (a common minimum for one-half of the arc engaged under rated load) the separation is about $46\frac{1}{2}$ one-hundred-thousandths, which is almost one-half of a thousandth. The result of such co-operating circular curves is that, as indicated in Figure 3, the ball is, transversely, in the nature of a rounded wedge against the co-operating raceway surface and, therefore, not only must considerable relative approximately-radial movement (as that of compression or indentation) occur between ball and race-ring in order to obtain load-supporting contact between those members at only a few degrees away from the point of tangency, but also that relative movement must be almost one-half of a thousandth of an inch to permit such load-supporting contact over even the customary

minimum arc. To permit such relative movement the material between the limits of such contact arc is necessarily correspondingly compressed or displaced and the resultant stress varies with each unit of length of the contact and is most concentrated at the initial point of tangency. One result of this is that undue stress is placed upon the intermediate portions of the engaged arc in order to permit any contact at all between the arc's terminal portions, and, consequently, the life of the device is limited by the endurance capacity of that small, central portion of the arc that is subjected to the greatest strain. Were it attempted to overcome this difficulty by simply making the whole surface, as 5, of the race-member to the same circular curve as that of the co-operating ball, that part of that race surface engaging the ball beyond the above-indicated arc of contact would create so much friction as the rolling ball rubs against it that even more detriment would occur to the bearing, it being detrimental to a bearing, and uneconomical from the standpoint of efficiency, to have the contact arc too long, the economical arc being that which includes only those bearing-member portions whose advantageous properties (as that of sustaining load) are not outweighed by their disadvantageous properties (as that of producing detrimental friction); and if such circular race-curve were abruptly stopped at the ends of that economical arc of contact, detrimental stress would occur at those ends. A second difficulty resulting from the above-mentioned relatively great compression or displacement is that the bearing parts (as the race-members 1 and 2) correspondingly relatively move out of initial, and intended, position with respect to each other, and, consequently, their respective connected machine-parts (as, for example, the casing and bevelled pinion of an automobile transmission) likewise shift from their initial and intended positions, with consequent detriment, such, for example, as mis-engagement of gears with resultant noise, loss of power, and other evils.

The clearances resulting from my invention overcome the difficulties above indicated and otherwise impart advantages. Line 12 of Figure 4 approximately states those clearances when employing a one-half inch ball and the above-indicated arc of the ellipse whose equation is given above. As shown by that table, there is little or no appreciable clearance for a distance that extends over several degrees of the contact arc and at even ten degrees from the center the clearance is but slightly more than one one-hundred-thousandth of an inch—a distance that is not one-tenth of that occurring at the same point when the typical circular raceway is employed, and that is no greater than the distance obtaining at less than a third of that arc when employing the circular curve—while at twenty degrees from the center (which is not infrequently the limit of the contact arc) the clearance of the elliptical curve is only about one-fifth of that occurring with the circular race, being less than one ten-thousandth of an inch, and at even twenty-five degrees (about the maximum for contact arcs heretofore employed) the clearance is barely over two ten-thousandths and is little more than one-fourth of that which results with the circular curve. Therefore, when a device employing the above-stated elliptical curve is free from load, the opposing surfaces of the co-operating load-supporting members are but very slightly spaced apart at any point in the whole

arc of inter-engagement under load, and over a large proportion of that arc (about half of it) they are in actual or substantial coincidence, their separation there being so slight that even 5 a negligible load (as one applied by the mere hand) will cause interengagement, so that in obtaining a typical total contact arc of about forty-four degrees (twenty-two degrees upon each side of the center) although with the previously-employed 10 circularly curved raceway that center must compress or be deflected more than 56 one-hundred-thousandths (more than half of a thousandth), with my elliptically curved raceway the deflection is but 13 one-hundred-thousandths 15 (about one and a third ten-thousandths). Moreover, it is known that when opposed circular curves are used, the shape of the whole contact area when under load is that of an ellipse whose center is the point of tangency of those curves 20 (thus showing markedly unequal stress per unit of length of contact); but with my device the gas-discoloration process shows that, with the exception of advantageous very short "tapering-off" extremities, 14, Figure 2, the whole contact 25 area under load is substantially rectangular, as indicated at 15, Figure 2, thus confirming the mathematical calculation that throughout all but these slight extremities the stress under load is substantially uniform per unit of length. Thus, 30 the result of the new structure is that when load is applied no deflection or compression of material to any substantially appreciable amount is necessary to afford the length of contact requisite for sufficient support, and, also, each unit 35 of that length of contact is subjected to substantially the same amount of stress. Consequently, amount of displacement and flexure of material of such contact area is greatly reduced. Furthermore, not only is the stress more evenly 40 distributed throughout each contact area, but also the total load is better distributed among those several balls of the bearing that are in the loaded zone. As a result the device is given great endurance (especially against failure because of 45 constant flexing of material), and there is greatly reduced approach between the supporting and supported parts (as the race-rings 1 and 2) when load is applied. And this is true under even the lightest loads as well as under the maximum for 50 which the device is rated.

In devices of this character it is highly advantageous, as previously intimated, to avoid abrupt ending of the line of contact and stress (so that detrimental stress forces may not concentrate at 55 such an abrupt end), and my above-described relationship between the opposing faces of the load-supporting members (as the race-rings 1 and 2 and the balls 3) effectually accomplishes this. Again referring to line 12 of Figure 4 it 60 will be seen that up to about ten degrees from the center, the rate of departure of the race curve from the curve of the co-operating ball is almost nothing and almost constant, the resultant clearances increasing only about one-eighth of one one-hundred-thousandth of an inch per degree; then for about the next eleven degrees the rate 65 of such departure slightly accelerates; and beyond that there is an increasingly great acceleration. The result of this is that although the 70 transverse contour of the race-member throughout its whole contacting portion, and even for a safe distance beyond that portion, is a smooth, regular, and gradual curve and thereby avoids abrupt breaks with their consequent stress-concentration, and although that race-member lies

extremely close to its co-operating rolling-member across the desirable arc for efficient load support, nevertheless that race surface is safely and relatively-quickly carried beyond reach of the co-operating ball at the limits of the useful and economical arc of contact, thus effecting the desirable "tapering-off" of stress, as indicated at 14 in Figure 2, and also avoiding any "side" contact between raceway and ball that would produce detrimental friction due to rubbing between 10 those parts.

In such devices as ball bearings constructed in accordance with my invention the increased resistance that the above-mentioned stress-distribution presents to compression or deflection of 15 material is such that the extent of arc of contact under a given load remains about the same as that of the profitable or economical arc heretofore used, for the same load, in devices having circular curves in opposition. But I find that in 20 my device I can increase such economical arc, because the substantially even distribution of stress over such arc (with the consequent elimination of concentration of penetrating force in the intermediate portion of the arc) so greatly increases 25 the fixity of the parts as respects each other (the "rigidity" of the device) as to more than off-set the effect of any rubbing friction resulting at the extended arc portions. Moreover, this gain in length of economical arc enables a lesser number 30 of balls, or other rolling-elements, to support a given load (I have found that while still confining the contact arc to an economical length, ten balls in my present device will support at least twice as much load as will fourteen balls in 35 a similar device having the circular curve transverse the raceway), and this is advantageous, not only in that it reduces cost by economizing as to material, but also in that for a given load the total amount of "side" friction (for the bearing 40 as a whole) due to the lesser number of balls rubbing upon the aggregate amount of longer contact arc is no greater than such total amount produced by the larger number of balls when acting upon the shorter arc; also, as I prefer to assemble the lesser number of balls of a given 45 diameter in the same-diameter race-rings that previously contained the greater number of balls of that diameter, the increased spaces thus resulting between balls gives greater opportunity 50 for cooling of race-ring points between periods of contact by the successive balls.

Furthermore, devices constructed according to my invention can, if desired, have filling-slots (indicated at 16, Figure 1, by the broken lines), because even if the filling-slot should extend somewhat into the total area of contact under maximum rated load, there is actual or substantial conformity between the periphery of the rolling member and the co-operating face of the race-member over a large middle portion of that area and no pressure above the average is necessary in the neighborhood of the filling slot to bring about the above-described rigidity and uniformity of stress.

But also, if desired, devices according to my invention can have their economical lengths of contact less than those above mentioned, as, for example, to provide such a restricted arc of 70 contact in an antifriction bearing that under maximum rated load the rolling-element will roll clear of a filling-slot end. One ellipse to whose curve the above-described race curve can for such purpose be modified to co-operate with 75

a ball one-half inch in diameter is that defined by the equation

$$\frac{x^2}{(.36189)^2} + \frac{y^2}{(.30079)^2} = 1$$

5 and indicated at 17 in Figure 1. The approximate radial distances between the ball and such a race curve are given in line 13 of Figure 4 and will be seen to be much less than the distances resulting from the circular raceway.

10 In some instances, as, for example, when the bearing device is a variable-speed power transmission, it is advantageous to make the race-member flat or of a circular curve and to employ a co-operating rolling-element that is a relatively narrow disc whose transversely curved periphery engages the race-surface, and in such instances I prefer to construct such transverse curve of the rolling-element upon that elliptical 15 arc whose center is in the ellipse's minor axis 20 rather than in the major axis.

It will be apparent that my characteristic inter-relationship and clearances between the load-supporting elements of my device can be obtained by many other curves than those of the circles 25 and the ellipses whose diameters or equations are above given, and that those characteristics can also be obtained by many other lines than those of circular curves opposing elliptical curves. For example, the closely-conforming portion of the 30 race (say, for an included angle of 45 degrees) can be the actual circular curvature of the co-operating ball, and beyond that arc the race surface can be so far removed from the ball that no contact will occur under maximum rated load, 35 but in such event I prefer to join the contact arc and the outlying non-contacting portions by smooth and gradual curves, so that no abrupt changes of line will be presented. One method of making such a circular-curve contact area is 40 by producing an elliptical curve as previously described and then using the designed co-operating ball, or its equivalent, to lap the contact area to the desired arc of the ball circle.

Thus, although my present device affords desired economical extent of contact between the load-supporting elements and avoids both detrimental engagement beyond such contact area and stress-concentration at the ends of such area, it also has substantially even distribution of stress 50 per unit of length over substantially the whole contact area even when subjected to the highest loads, and possesses great endurance properties and rigidity.

I claim:

65 1. In a device of the character indicated, co-operating load-supporting members, the transverse surface of one of which when the device is free from load is a curve whose central portion engages the other said member in substantially the line of load, said curve as it progresses from said point of engagement first minutely increasing departing from the direction of the surface of the said other member over a substantial proportion of the length of contact under 60 normal load and then relatively rapidly increasing its rate of such departure until as said curve passes beyond said length of contact it is spaced from said other member by a distance greater than that obliterated by application of the load; substantially as described.

70 2. In a device of the character indicated, co-operating tangent load-supporting members that are curved transversely, one of said members being non-circular, and said members having sub-

stantially the same radius of curvature at said point of tangency, and over a substantial portion of the arc of contact under normal load minutely separating from each other as said point is proceeded from and then over the remainder of said arc more rapidly so separating; substantially as described.

5 3. In a device of the character indicated, co-operating load-supporting members whose engaging surfaces are related to each other substantially as are a circular arc and an elliptical arc which has its central point in an axis of the ellipse and tangent to said circular arc in substantially the line of load, such central portion of said elliptical arc being substantially the same 15 curvature as is said circular arc; substantially as described.

10 4. In a device of the character indicated, co-operating load-supporting members whose engaging surfaces are related to each other substantially as are a circular arc and an elliptical arc which has its center tangent to said circular arc in substantially the line of load, said elliptical arc being very nearly the curve of such circle throughout substantially the arc of contact under 20 load and first only minutely progressively departing from said circular curve as said elliptical curve proceeds from said point of tangency, then appreciably accelerating its rate of such departure as the extremities of said arc of contact 25 are being reached, and then relatively rapidly 30 further increasing such rate for the portions that pass beyond said extremities; substantially as described.

5 5. In a device of the character indicated, co-operating bearing-members which are transversely curved in lines that are related to each other substantially as the circumference of a circle of one-half inch diameter is related to an 35 ellipse defined by the equation

$$\frac{x^2}{(.34602)^2} + \frac{y^2}{(.29412)^2} = 1$$

40 substantially as described.

6. In a device of the character indicated, co-operating load-supporting members whose surfaces in the region of contact under load are spaced from each other substantially as are a circular arc and a co-operating elliptical arc of the region of the vertex on the major axis of the 45 ellipse, said arcs being tangent at the said vertex; substantially as described.

7. In a bearing, cooperating bearing elements having curved opposing surfaces, the curve of one of said elements being unitary and having a vertex, and having, at said vertex, a radius substantially the same as that of the other said element and also having, at points upon opposite sides of said vertex, a radius greater than that of said other element; substantially as described.

55 8. In a device of the character indicated, co-operating load-supporting members having engaging surfaces of which one is a circular curve and the other is a non-circular curve having a vertex which engages the other said member under load, and has a radius of curvature substantially the same as that of said circular curve; substantially as described.

60 9. In a device of the character indicated, co-operating rolling load-supporting members of 70 curved transverse cross-section, one of such curves being initially of a variable curvature more closely approaching the curvature of the cooperating said member at the arc of contact under normal load than at adjacent regions, and 75

also being initially in contact with said cooperating member at the central portion of said arc; substantially as described.

10. In a device of the character indicated, co-operating tangent load supporting members which are curved transversely and one of such curves being non-circular, said members initially

engaging at the vertex of the curve of one of them, and the radius of such curvature of the one said member at said vertex being substantially the same as that of the other said member; substantially as described.

also being initially in contact with said cooperating member at the central portion of said arc; substantially as described.

10. In a device of the character indicated, co-operating tangent load supporting members which are curved transversely and one of such curves being non-circular, said members initially

engaging at the vertex of the curve of one of them, and the radius of such curvature of the one said member at said vertex being substantially the same as that of the other said member; substantially as described.
